United States Patent Office.

JOSEPH WARREN, OF LODI, OHIO.

Letters Patent No. 77,227, dated April 28, 1868.

IMPROVEMENT IN CORN-SHELLERS.

The Schedule referred to in these Letters Patent and making part of the same.

TO ALL WHOM IT MAY CONCERN:

Be it known that I, JOSEPH WARREN, of Lodi, in the county of Medina, and State of Ohio, have invented certain new and useful Improvements in Corn-Shellers; and I do hereby declare that the following is a full and complete description of the same, reference being had to the accompanying drawings, making a part of this specification, in which—

Figure 1 is a side view of the machine.

Figure 2 is a transverse section.

Like letters of reference refer to like parts in the views.

This sheller consists of the case A, (fig. 1,) mounted upon and secured to the legs B. In this case is hung a disk, C, (fig. 2,) upon the shaft D, having its bearings in the centre of the case. On one of the protruding ends of said shaft is keyed a fly-wheel, E, and upon the opposite end a crank, F, by which the machine is operated.

One face of the disk referred to is thickly studded with teeth, G, whereby the grain is shelled from the cob, as will hereafter be shown.

H is the hopper, into which the ears are thrown, I the spout, from which the corn flows, and J the opening from which the cobs are discharged from the machine.

I am aware that a corn-sheller having a case, toothed disk, hopper, wheel, and crank, all constructed and arranged in a manner analogous to this, is now in use, but the case of the machine referred to is made with a full convex side, as indicated by the dotted line α , thereby giving a large amount of room in and around the shaft D.

In consequence of this great space the cobs accumulate about the shaft, and by their lodgment there obstruct the proper working of the machine. The cobs, unless removed, are more or less ground up or broken, and the dust and fragments drop through the spout along with the shelled corn, rendering it dirty and unmarketable unless cleaned.

To avoid this defect of the machine, I construct the side facing of the disk as represented in the drawing, in which it will be seen that the side, instead of being of a uniform convex surface, is depressed at the points α around the shaft, thereby contracting the room to a much less holding-capacity, so that the cobs can find no room to accumulate, but are carried off along, through, and out of the tube J.

This tube, as will be seen, is simply a swell around near the margin of the side, extending from the hopper around to the opening K in the side of the case, forming a semicircular channel of only sufficient capacity to allow the passage of a single cob at a time, thereby preventing them from becoming crossed and tumbled about in the central portion of the case and around the shaft, as above said.

By this peculiar shape given to the side of the case, no accumulation or lodgment of the cobs in and around about the shaft can take place, hence the grain will at all times come from the machine free of dirt and fragments of cob. The machine never becoming obstructed, no time is lost in removing the obstruction, which so often results in the use of the ordinary sheller.

What I claim as my improvement, and desire to secure by Letters Patent, is—

The case A, having one of its sides provided with a circular depression around the axis of the disk, in combination with the segmental discharging-tube J, in the manner and for the purpose specified.
